CLAIM

The ornamental design for a reusable coffee pod filter, as shown and described.

DESCRIPTION

FIG. 1 is a front, perspective view of the reusable coffee pod filter of the present invention;

FIG. 2 is a front view of the reusable coffee pod filter shown in FIG. 1;

FIG. 3 is a right view of the reusable coffee pod filter shown in FIG. 1;

FIG. 4 is a back view of the reusable coffee pod filter shown in FIG. 1;

FIG. 5 is a top plan view of the reusable coffee pod filter shown in FIG. 1;

FIG. 6 is a left view of the reusable coffee pod filter shown in FIG. 1; and,

FIG. 7 is a bottom plan view of the reusable coffee pod filter shown in FIG. 1.
